US00D988311S

(12) **United States Design Patent** (10) **Patent No.:** **US D988,311 S**
Yun et al. (45) **Date of Patent:** **** Jun. 6, 2023**

(54) **PORTABLE DISPLAY DEVICE**

(71) Applicant: **LG DISPLAY CO., LTD.**, Seoul (KR)

(72) Inventors: **YoungJoon Yun**, Paju-si (KR); **Seungo Jeon**, Paju-si (KR); **ShinSuk Lee**, Paju-si (KR)

(73) Assignee: **LG DISPLAY CO., LTD.**, Seoul (KR)

(**) Term: **15 Years**

(21) Appl. No.: **29/657,310**

(22) Filed: **Jul. 20, 2018**

(30) **Foreign Application Priority Data**

Nov. 23, 2017 (KR) 30-2017-0054902

(51) **LOC (14) Cl.** **14-02**

(52) **U.S. Cl.**

USPC **D14/341**

(58) **Field of Classification Search**

USPC ..... D14/138 AA, 138 AB, 138 AC, 138 AD, D14/138 C, 138 G, 248, 314, 315–318, D14/341–347, 371, 374; D10/50, 65, D10/104.1; D19/26, 59–60, 113; D21/324, 329–330, 332

CPC ... H04M 1/0202; H04M 1/0266; H04M 1/725

(57) **CLAIM**

The ornamental design for a portable display device, as shown and described.

DESCRIPTION

FIG. 1 is a front, right, top perspective view of the portable display device showing our new design in a folded state;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a front, right, top perspective view thereof in an unfolded state;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom view thereof.

The broken lines shown in the figures are for the purpose of illustrating portions of the portable display device that form no part of the claimed design.

1 Claim, 14 Drawing Sheets
